UNITED STATES PATENT OFFICE.

STANLEY J. VESELY, OF CEDAR RAPIDS, IOWA.

LIFTING JACK.

Application filed April 12, 1926. Serial No. 101,468.

This invention relates to jacks for lifting heavy loads, being designed more particularly for use in connection with motor vehicles. The object of the invention is to produce a simple, easily operated and powerful jack, stable and reliable in operation, and having a wide range of movement and composed of comparatively few parts.

The invention is fully disclosed in the description and claims following, reference being had to the accompanying drawing, in which:—

Fig. 1 is a side elevation of a jack embodying the invention not quite fully extended, the middle portion of the jack being mainly in section. Fig. 2 is a central, vertical section of the same fully collapsed. Fig. 3 is a similar section of a modification in the structure of the jack, partly extended.

20 A part of the following description applies to Fig. 3, as well as Figs. 1 and 2. The differences will be pointed out explicitly hereafter. Figs. 1 and 2 will be first described in detail.

25 In the drawing the numeral 5 denotes a base, which should be provided with a bearing 6 to carry a stub-shaft or spindle 7 adapted for connection with an operating wrench or the like turning device, not shown.

30 A pinion 8 at the inner end of the shaft engages a bevel gear 9 forming a part of the driving mechanism of the jack, as will appear presently.

To the base is rigidly secured a stiff, screw-threaded post 10. Assuming that the shaft 7 is to be turned clockwise for lifting, the screw-thread of the post will be a left-hand screw, as shown. On this post is screwed a long tubular nut (practically as long as the post), 40 and expanded at the upper end to form an externally threaded screw. This nut 11 and its head 11^a serve as a screw connection between the post and a concentrically disposed, tubular, internally threaded member 12,

45 which is the part of the jack directly applied to the load, and for convenience will hereafter be referred to as the ram, and the connecting nut as the coupler. In operation the ram is held from turning, and as the threading of its screw is of the opposite (right-hand) type, it is evident that the turning of the coupler will elevate or depress the ram as it, (the coupler) runs up or down on the post. Assuming the pitch of the threads to be the same, the ram will move

twice as far as the coupler, considered with respect to the base.

The coupler is turned by a tubular member 2, hereafter referred to as the driver, which engages the coupler slidably but unturnably. Preferably the shank of the coupler is angular in cross section (hexagonal in the drawing), and fits slidably inside a corresponding bore in the driver. To facilitate the turning of the driver it is provided with a bevel gear 9, as above mentioned. The drive-shaft is preferably inclined, as shown in Figs. 1 and 2 for the convenience of the operator. To give the greatest possible extension of the jack, determined by the length of its several sections, the bevel gear should be at the extreme lower end of the driver. In the type of jack shown in Figs. 1 and 2 there is no end-thrust on the driver, the entire weight being carried by the post and its screw-threaded connecting parts. This makes the turning of the driver easy, and permits the use of the bevel gear as an auxiliary basal support, the wide gear tending to prevent undue tipping of the lifting parts of the jack, since it runs on or close to the base.

For many purposes the parts above described make a complete, operative jack. In operation the ram needs to be held from turning (if it is to be screwed up, rather than merely carried up by the coupler), but ordinarily it is so held by the load it lifts. Any tendency of the jack to tip or deflect from a vertical line is counteracted by the rigid post and the screw connections of all the parts extensible in the lifting operation. Such a jack would not be so convenient, in many ways, as the fully equipped jack, but it would be entirely practical and operative. It is preferred, however, to provide means for preventing the turning of the ram, and also, in some degree, increase the rigidity of the jack when fully extended. This includes a sleeve 13, slideable, but unturnable on the ram, and a guide 14 for the sleeve forming a rigid part of the base. A slot 13^a in the sleeve takes a stud 15 attached to the ram. A similar slot 14^a takes a stud 16 attached to the sleeve. The upward movement of the parts is limited by the engagement of the studs with the ends of the slots.

The principle of the jack shown in Fig. 3 is essentially the same as the other, but in this case the driver is screw-threaded and

engages the lower, closed end of the sleeve, so that it is raised concurrently with the coupler. The characters 13^e and 11^e are used to distinguish this sleeve and coupler from the corresponding parts in Figs. 1 and 2. A ball bearing is shown for the driver 2, but any bearing will serve, as there is practically no end-thrust on the driver.

In the type of jack shown in Figs. 1 and 2 the collapsing of the parts is forced by the positions of the gears. In that shown in Fig. 3 a bracket 17 serves the same purpose.

Having thus described my invention, I claim:

15. 1. In a lifting jack, a base, a screw-threaded post rigidly attached thereto, an internally and externally, oppositely threaded coupler engaging the post, a tubular ram screwing on said coupler, a tubular driver disposed relatively between the ram and the coupler when in collapsed position, and engaging the coupler slidably but unturnably, and means disposed at the base for turning the driver.
25. 2. In a lifting jack, a base, a screw-threaded post rigidly attached thereto, a tubular, internally threaded ram, a sleeve engaging the ram slidably but unturnably, a rigid guide to permit the endwise, but prevent rotary movement of the sleeve, a doubly and

oppositely screw-threaded coupler to engage both the ram and the post, and a driver engaging the coupler slidably, but unturnably, and disposed between the coupler and the ram when the jack is collapsed.

3. In a lifting jack, a base, a rigid, screw-threaded post rising therefrom, a tubular coupler screwing on said post, and having an expanded, oppositely threaded head, a tubular ram screwing on said head, and a 40 tubular driver disposed in the space between the ram and coupler when in collapsed position, and adapted to turn the coupler as said coupler slides in the driver.

4. In a lifting jack, a base, a rigid screw-threaded post rising therefrom, a coupler threaded to run on the post, and having an expanded head externally threaded, a tubular ram threaded to run on said head, an endwise movable member engaging the ram and adapted to prevent its turning, a screw-threaded driver engaging said movable member by its screw thread, and slidably, but unturnably engaging the coupler, and means adapted to turn the driver, 50 whereby concurrent and positive movement is imparted to the extensible parts.

In testimony whereof I affix my signature.

STANLEY J. VESELY.
